OTTO THIEME, OF ST. LOUIS, MISSOURI, ASSIGNOR TO MOON HOPKINS BILLING MACHINE COMPANY, OF ST. LOUIS, MISSOURI, A CORPORATION OF MISSOURI.

BACK-SPACING MECHANISM.

1,204,612.

Specification of Letters Patent.

Patented Nov. 14, 1916.

Application filed May 3, 1915. Serial No. 25,457.

To all whom it may concern:

Be it known that I, OTTO THIEME, a citizen of the United States, residing at city of St. Louis, State of Missouri, have invented a certain new and useful Improvement in Back-Spacing Mechanism, of which the following is a full, clear, and exact description, such as will enable others skilled in the art to which it appertains to make 10 and use the same, reference being had to the accompanying drawings, forming part of this specification, in which—

Figure 1 is a detail skeletonized view of my improved carriage shifting mechanism. 15 Fig. 2 is a front elevational view. Fig. 3 is a side elevational view. Fig. 4 is a vertical sectional view through the laterally movable paper carriage.

This invention relates to a new and useful improvement in carriage shifting mechanisms for calculating machines, the object being to automatically position the carriage containing a platen for supporting a sheet of paper whereby data, which may be written 20 by the typewriting mechanism, may be identified with certain items introduced into the calculating mechanism. For instance, in banking transactions where, to expedite matters in the clearing house, it is desirable 25 to employ the number of the bank on which the check is drawn and the number of the bank in which the check is deposited—these numbers may be set up on the typewriting mechanism as, for instance, 34—56, and then, 30 without employing the tabulating keys of the typewriting mechanism or manually shifting the carriage, the amount of the check, as for instance, \$23.45, may be set up on the digit keys of the adding machine, 35 after which the handle of the calculating machine may be pulled, or the motor key which controls the main operating shaft of the calculating machine may be operated so as to introduce the item into the accumulating 40 mechanism of the calculating machine. 45

In the type of machine to which my invention is designed particularly to be applied, such for instance as is illustrated in French Patent No. 383,719, dated January 50 16th, 1908, the forward pull of the handle, equal to the downward pull of the motor operated link, positions the racks 100 before there is any engagement between said racks and the accumulator wheels 119. I utilize 55 this first half stroke of the machine to shift

the carriage so that the item \$23.45 may be printed to one side, preferably the left of the numbers of the banks, to wit: 34—56, as follows:

\$23.45	34—56	60

When the racks reach their forward position, the printing mechanism of the calculating machine is operated to make the printing impression and the backward movement 65 of the racks results in introducing the item into the accumulator wheels, the returning movement of the operating shaft also operating the line-spacing mechanism so as to rotate the platen and position the paper for 70 another operation.

The second operation, like the first, may be performed by printing, with the typewriting mechanism, the number of the bank on which the check is drawn, the number of the 75 bank which is entitled to credit for the check and in which the check is deposited, then, without moving the typewriter carriage, proceeding to set up the number on the key board of the amount of the check. If this 80 is \$545.67, for instance, that amount would be set up on the key board of the calculating machine and the motor key operated, the operation of the motor key on the first half stroke positioning the carriage so as to print 85 the number \$545.67 directly under and in proper position relative to the first item \$23.45, as follows:

23.45	34—56	90
545.67	235—678	

This operation of identifying the banks by the typewriting mechanism and setting up the items constituting the amounts of the checks on the key board of the calculating machine being continued, the operation of the calculating machine positioning the carriage and its platen-supported paper properly, thus rendering it unnecessary to utilize the tabulating keys and also returning the 95 carriage to normal position. Thus, assuming that five thousand of such items are set up in the machine in a day's work, five thousand operations of the tabulating keys will be saved and as many return movements 100 manually restoring the carriage to normal position will likewise be saved.

While I have mentioned banking transactions, it is obvious that the machine is capable of use in other transactions as, for 105 110

instance, amounts of premiums paid on life insurance policies and the numbers of such policies may be tabulated, the premiums being accumulated and the totals thereof obtained; likewise, the numbers of cars and the tonnage of each car may be tabulated and the total tonnage obtained, etc. It is obvious of course that instead of employing numbers to identify certain items which are listed and accumulated, words may be written by the typewriting mechanism, such as States or other data necessary to identify the listed items.

Instead of writing in the dates, numbers or other identifying data on the typewriting mechanism in the first instance, it is obvious that the items to be listed and accumulated may be first set up on the key board of the calculating machine, the operation of the digit keys of the calculating machine not operating the escapement mechanism of the carriage as in letter-spacing operations, but permitting said carriage to remain laterally immovable, after which the typewriter keys may be operated and coincidentally therewith the letter-spacing escapement mechanism will be operated so as to position the carriage from right to left.

The carriage shifting mechanism herein-after described positions the carriage from left to right and I have found that the sweep of the carriage shifting arm should, for ordinary operations, include not less than fifteen letter-spacing positions of the carriage, thus permitting fifteen identifying characters to be written by the typewriting mechanism. Within this range of fifteen characters, the sweep arm will restore the carriage to normal position. It is of course obvious that the sweep arm could be made longer to include a greater range of identifying characters, or the arm could be made shorter to include a shorter range of identifying characters, if it was found that a less number of identifying characters could be used.

In the actual operation of the machine, if the carriage is stepped over four spaces in the writing in of four identifying characters, the carriage will be returned four spaces to its original position; or, if 6, 9, 12, or 15 identifying characters are employed and the carriage stepped leftwardly a corresponding number of spaces, it will be restored just exactly the number of spaces stepped leftwardly by the typewriter keys. In this respect, my device differs from the so-called "shuttle mechanisms" for shifting carriages a predetermined distance at each operation.

The carriage shifting mechanism which will restore the carriage a variable distance depending upon the number of identifying characters written in by the typewriting mechanism is only operative with respect to the carriage when the carriage is in certain

positions, or rather when the adjustable block on the carriage, with which said shifting mechanism co-operates, is in a certain position, said shifting mechanism being normally not in control of the carriage, which permits the carriage to be shifted laterally in letter spacing operations without requiring any special adjustment of the parts. This is accomplished by pivoting the sweep arm so that in its normal position, it will lie below the path of travel of its co-operating adjustable pin on the carriage, thus permitting the carriage and its pin to move over the sweep arm in ordinary typewriting operations without interference; but, when the adjustable pin on the carriage is moved in the path of movement of the sweep arm, the carriage will be restored to a predetermined position at each operation of the operating shaft of the calculating machine.

In the drawings, I have shown a motor driven machine in which 1 indicates the base plate upon which the typewriting and calculating mechanisms are mounted.

2 are posts for supporting the top plate 3 of the typewriting mechanism, and 4 is the side frame plate of the calculating machine.

5 is the laterally movable carriage containing a platen 5^a, under which the paper to be printed upon is passed and supported. The keys of the typewriting mechanism, one of which a is shown in dotted lines, force the type b against this paper on its under side, to the right of the printing point of the type c of the calculating machine, so that words and figures may be printed thereon, as in the manner well known with respect to typewriting machines. The printing point of the typewriting mechanism is preferably to one side, the right of the printing point or line of type positioned by the calculating machine, but it may be to the left, if desired, all as set forth in the patent to which reference has heretofore been made.

6 indicates a motor for operating the main operating shaft of the calculating machine by means of a link 7 which link is connected to a rock arm extending from the operating shaft 8. This motor is controlled by a motor key 9 connected by a rod 10 to a sliding bar 11 which is provided with an inclined face for raising the clutch releasing bar 12. The details of this motor drive form no part of my present invention and need not be further described.

13 indicates an arm loosely mounted on the shaft 8 and resting upon a pin 14 extending from the operating link 7. The forward end of this arm 13 is held down by a spring 15, said forward end being connected by a rod 16 to a bell crank lever 17 pivotally mounted on a bracket secured to the top frame plate 3 of the typewriting mechanism. In its normal position, the sweep member of this bell crank 17 lies below the horizontal

plane of travel of a pin 18 mounted on a block 19. This block 19 is adjustably mounted on a notched bar 20, secured to the frame 4 of the laterally movable carriage, so that the listing of identifying items may be done at different points on the sheet of paper being printed upon. I prefer to have several adjustable blocks as shown in Fig. 1 so that two or more columns of identifying items 10 may be printed on the same sheet of paper side by side, if desired. It is, of course, obvious by referring to Fig. 1 that when the end of the sweep arm 17 lies under the pin 18, the typewriting mechanism can be operated and the paper carriage letter-spaced without any interference whatever from the sweep arm. However, in the tabulating work for which this machine is expressly designed, one or more of the blocks 18 are 20 properly positioned. The carriage is then adjusted so as to place a pin 18 within the sweep of arm 17. This can be determined by pressing the motor key and ascertaining that the paper carriage is moved by the sweep 25 arm one or more steps to the right. Then as a number is set up in the adding mechanism and the carriage advanced leftwardly up to the range of the sweep, said sweep arm will return the carriage to its original starting 30 position upon the operation of the motor key. Of course, if the carriage is stepped leftwardly so as to move the pin 18 beyond the sweep of the arm 17, the carriage will be beyond the control of the sweep arm and 35 will have to be again placed under control of said sweep arm by manually positioning said carriage rightwardly.

In operation, assuming that the parts are in the position shown in Fig. 2, an item to be 40 listed and accumulated may be set up on the key board of the calculating machine, the depression of the keys of which not effecting a lateral step by step movement of the paper carriage, after which identifying letters or 45 numbers may be written on the paper by means of the typewriting mechanism. The operation of each typewriter key will move the carriage leftwardly step by step and whether one or more characters are type- 50 written on the paper up to the range of the sweep arm, the pin 18 will be operated within the arc of movement of the sweep arm and under control of said sweep arm. Of course if the pin 18 passes over and to the left of 55 the sweep arm, the operation of the sweep arm will not coöperate with the pin and consequently the carriage will not be returned, but in ordinary operations this will not happen and the pin 18 will be left, after 60 typewriting identifying characters, to the right of the sweep arm so as to be under the control thereof. When the motor key is operated to introduce the number set up on the key board of the calculating machine 65 into the accumulator wheels 119, through

the medium of the racks 100, (said racks carrying printing type *c* at their forward ends, as shown by dotted lines in the drawings, and fully described in the patent before referred to) the first half stroke of the operating shaft in which the link 7 is drawn down, will, through the spring 15 draw the arm 13 down and rock the sweep arm 17 toward the right. The sweep arm will engage the pin 18 and move the carriage toward the right a number of spaces equal to the number of identifying characters written by the typewriting mechanism, whether one or more, up to the range of said sweep arm, during which movement of the carriage toward the right, the rack bars 100 are moved forwardly out of engagement with the wheels 119, until they are arrested by their controlling stop pins. In starting the second half stroke, or what would be equivalent to the backward movement of the operating handle, if an operating handle was used, the link 7 rises and forces the arm 13 upwardly, restoring the sweep arm to its normal position. The accumulator wheels 90 119 are thrown into mesh with the racks so as to introduce the item therein, and the printing mechanism of the calculating machine is operated to make a record or "list" the items set up on the key board. After 95 the item is listed, the line-spacing mechanism will be operated to rotate the platen and advance the paper for another printing operation.

The above described operations are repeated, it being immaterial whether the identifying characters are first written on the sheet of paper by the typewriting mechanism before or after the item to be identified, listed and accumulated in the calculating 100 machine is potentially set up to be introduced into the calculating mechanism.

In Fig. 1 I have shown the spacing bar 21 which is carried on the forward ends of levers 22, the rear ends of said levers containing a rod 23 from which is mounted a link 24 for operating the pivoted escapement pawl 25, which coöperates with the rack bar 26 on the paper carriage. These pawls are under control of a rocking plate 27, operated by a bar 28, whereby the escapement pawls may be thrown out of operative relation to the rack bar, by means of tabulating keys. In this manner the carriage may be stepped leftwardly upon the operation of 110 any one of the typewriter keys, or by disengaging the escapement pawls either by the tabulating keys, or a lever on the carriage, not shown, the carriage may be moved leftwardly. The stops for the tabulating keys 115 are not illustrated in the drawings, as the same form no part of my present invention.

The means for operating the paper feeding pawl 30, which coöperates with the ratchet on the end of the platen, is also 120 125 130

shown in Fig. 4, the same consisting of an arm 31 which is operated from some moving part of the calculating machine, the outer end of said arm engaging over a stationary 5 lever 32 having a pin 33 which rides over a rod 34 extending throughout the length of the carriage, said rod being mounted in a rocking frame 35, which carries a line spacing pawl 30. In this manner the paper may 10 be line-spaced in any position of the carriage.

I do not in this application make any claim to the above described devices as applied especially to calculating machines, as 15 the same forms the subject matter of a companion application filed by me, June 4, 1912, Serial No. 701,518.

What I claim is:—

1. In a machine of the character described, the combination of a frame, a movable paper carriage on said frame, a stop adjustably mounted on said carriage, a lever mounted on said frame to engage said stop in its sweep and back-space said carriage, and means for rocking said lever.
2. In a machine of the character described, the combination of a frame, a

movable paper carriage, a stop adjustably mounted on said carriage, a member mounted on said frame and normally positioned to permit the free movement of said stop past said member, means for letter-spacing said paper carriage, and means for moving said member a predetermined distance to back-space the carriage to a predetermined position when said stop is in position to be engaged by said member when the latter is actuated.

3. In a machine of the character described, the combination of a frame, a 40 movable paper carriage, a stop mounted on said carriage, a member mounted on said frame, means for moving said member into engagement with the stop to back-space the carriage, and means for adjusting the position of said stop relative to said member.

In testimony whereof I hereunto affix my signature in the presence of two witnesses, this 26th day of April, 1915.

OTTO THIEME.
